OTHER PUBLICATIONS

Blue Medical Gown; Manufactured by Medline Industries, Inc.; Unknown availability date but believed to be prior to 1999.

(Continued)

Primary Examiner — Lakiya G Rogers*Assistant Examiner* — Carissa C Fitts(74) *Attorney, Agent, or Firm* — Philip H. Burrus, IV(57) **CLAIM**

The ornamental design for a medical gown, as shown and described.

DESCRIPTION

FIG. 1 is a front elevation view a medical gown illustrating my new design; and,

FIG. 2 is a rear elevation view thereof.

The broken lines form no part of the claimed design.
